Patented June 25, 1929.

1,718,571

UNITED STATES PATENT OFFICE.

FRED L. MANNY, OF BENTON HARBOR, MICHIGAN, ASSIGNOR TO F. P. ROSBACK COMPANY, OF BENTON HARBOR, MICHIGAN.

STAPLING MACHINE.

Application filed January 16, 1928. Serial No. 247,062.

The main objects of this invention are:

First, to provide a stitching machine which may be easily and quickly adjusted to space the stitching as may be desired for the particular work.

Second, to provide an improved stitching machine which is adapted for wide variation in the work.

Third, to provide an improved stitching machine which is of large capacity and at the same time compact and comparatively simple in structure.

Fourth, to provide an improved feed means for the work.

Fifth, to provide an improved stapling machine in which the spacing of the staples may be varied in the same piece of work.

Objects pertaining to details and economies of my invention will appear from the description to follow. The invention is defined in the claims.

A machine which embodies the features of my invention is clearly illustrated in the accompanying drawing forming a part of this specification, in which:

Fig. 1 is a front perspective view of my improved stitching machine, portions of the base being broken away.

Fig. 2 is a fragmentary rear perspective view of the delivery end of the machine.

Fig. 3 is a fragmentary rear perspective of the front end of the machine.

Fig. 4 is a detail front perspective with certain parts omitted for the purpose of better showing the relation of certain of the operating parts.

Fig. 5 is a detail view partially in vertical transverse section showing details of the driving and adjusting means.

Fig. 6 is a fragmentary front perspective showing details of the work feed mechanism.

Fig. 7 is a detail view partially in vertical longitudinal section on a line corresponding to line 7-7 of Fig. 5 showing further details of the driving mechanism.

Fig. 7A is a detail on line 7a-7a of Fig. 7.

Fig. 8 is a fragmentary rear perspective view showing details of the means for feeding the work through the stapler and of the conveyor delivering thereto.

Fig. 9 is a fragmentary front perspective view showing parts of the work feed conveyor shown in Fig. 8.

Fig. 9A is a detail section on line 9a-9a of Fig. 9.

Fig. 10 is a fragmentary front perspective view of the opposite end of the work feed conveyor.

Fig. 11 is a fragmentary rear perspective view of the work delivery conveyor or stacker. 60

Fig. 12 is a detail perspective view of the means for vertically adjusting the delivery conveyor.

Fig. 13 is a fragmentary rear perspective view showing details of the stapler or feed 65 drive mechanism.

Fig. 13A is a detail section on line 13a-13a of Fig. 13.

Fig. 14 is an inverted detail perspective view showing details of the staple feed driv- 70 ing mechanism.

Fig. 15 is a detail view partially in section on line 15-15 of Figs. 13 and 14.

Fig. 16 is a detail section taken on a line corresponding to line 16-16 of Fig. 13. 75

Fig. 17 is a fragmentary perspective view showing details of the driving clutch control mechanism.

Fig. 18 is a detail view mainly in section on line 18-18 of Fig. 17. 80

Fig. 19 is a fragmentary elevation showing details of the driving mechanism for the work feed rolls whereby variations in speed result, thereby effecting a variation in the spacing of the staples in the same piece of 85 work.

Figs. 20, 21 and 22 are fragmentary side elevations showing successive positions of the parts shown in Fig. 19.

Fig. 23 is a detail view mainly in section 90 on line 23-23 of Fig. 20.

Fig. 24 is a detail view mainly in section on line 24-24 of Fig. 20.

Fig. 25 is a perspective view of the stapler work guide. 95

Fig. 26 is a perspective view of one of the pieces of work showing a possible position in the spacing of the staples.

Fig. 27 is a fragmentary rear view of a 100 stack of work showing the offset relation or variations in spacing of the staples.

Referring to the drawing, the machine in the embodiment illustrated is supported on a base 1 having a projecting pedestal 2. On this pedestal is a gear or transmission box 3 105 the pedestal also forming a housing for certain parts of the driving connections as will appear as the description proceeds.

The stitcher head 4 is supported by an overhanging arm 5 on the upper end of the 110

pedestal. The details of the stitcher head other than the controlling mechanism thereof form no part of this invention. The details of the control mechanism of the stitcher head 5 which do constitute a part of this invention are fully illustrated.

The work in the form of a plurality of fold-
ers illustrated at 6, Fig. 26, is in the embodiment illustrated placed in the machine by
10 hand, a conveyor way 7 of A cross section
projecting forwardly from the standard. The front end of this way is supported by
an arm 8 projecting from the boss 9 on the
base 1. This conveyor way 7 has a longi-
15 tudinal slot at the apex thereof through
which the flights 10 of the conveyor project
to engage the work shown by dotted lines
in Fig. 1.

The conveyor comprises a conveyor chain
20 11 traveling on and driven by the sprockets
12 and 13, see Figs. 8, 9 and 10. These sprockets are fixed to the shafts 14 and 15, respectively, which shafts are mounted in bearings
25 16 and 17 carried by the bearing blocks 18
and 19. These bearing blocks are supported
by spaced rails 20 and 21 and are connected
by the rod 22 so that they are simultaneously
adjusted. The bearing block 16 is provided
30 with an index finger 23 operatively associated
with the adjusting indicia 24 on the front
rail 20. The bearing blocks have slots therein
to engage the inwardly projecting arms of the
rails and are secured in adjusted positions
35 by the set screw 270, a hand piece 271 being
provided to facilitate adjustment, see Fig. 9A.

The shaft 14 is provided with a beveled
30 gear 25 coating with a beveled gear 26 which
is slidably keyed to the shaft 27, the keyway
being indicated at 28. The shaft has a bear-
ing at 29 in the bearing block 18, the block
40 being slidable on the shaft.

The flights 10 are pivotally mounted in
45 spaced relation on the conveyor chain and
provided with arms 30 having rollers 31
thereon. The flights 10 are fixed to their
pivots 32 and the pivots carry tappets 33.
50 These rollers 31 and the members 33, while
the flights are traveling on the upper reach
of the conveyor, travel in and are supported
by the opposed channeled ways 34.

To retract the flights at the rear end of the
conveyor the ways 34 are provided with
55 downwardly curved retracting members 35
which to eliminate undue shock are pivoted
at 36. The rear ends of the retracting mem-
bers are supported by the spring 37. The
stop 38 limits the swing of these retracting
60 members on their pivots.

As the flights travel over the feed sprock-
65 ets 12 the tappets 33 engage with these re-
tracting members as the rollers 31 drop from
the supporting ways so that the flights are
retracted or tilted backwardly away from
the work as shown in Fig. 8. In order to in-
65 sure rapid retraction of the flights at this

point the flight retracting members 35 are
cammed at 39 so that as the flights move for-
wardly the tappets 33 contact with these cams
and the flights are swung abruptly backward,
70 withdrawing them through the slot in the work
conveyor way and releasing the work
without imparting any forward movement
thereto or wiping the flight downwardly on
the work.

In order to swing the flights to erect pos-
ition at the forward end of the feed conveyor,
I provide a pair of flight erecting guide mem-
bers 40 which are downwardly curved at the
80 sides of the sprockets so that as the flights are
carried over the front sprockets 13, the tap-
pets 33 and the rollers 31 are guided into the
ways 34 and the flights are thereby supported
in erect position projecting through the slot
in the work supporting way.

From this feed means or feed conveyor de-
85 scribed, the work is delivered to the stitcher
conveyor. To adapt the feed conveyor for
delivering work of different length to the
stitching conveyor means are provided for
adjusting the flights of the feed conveyor 90
relative to its actuating means. The mecha-
nism by which this is accomplished will, how-
ever, be described later.

The stitching conveyor includes a way 41
95 consisting of a pair of plates disposed at an
angle as are the plates forming the feed con-
veyor way 7, the plates forming the way 41
being spaced at their apexes to provide a con-
tinuation of the slots 42 through which the
flights project.

As the work is delivered by the feed con-
veyor to the stitcher conveyor it passes under
the bowed spring 43 which is supported at its
upper end with its lower end free and di-
rected rearwardly to frictionally engage the
105 work, acting as a drag to prevent overthrow
during its step by step movement as it is en-
gaged by the stitcher feed rollers, and also
to hold it down upon the way.

The work is further held in position and
110 in proper relation to the way stitcher by
means of the double cone roller 44 and the
retaining or guiding foot 46 disposed at the
rear of the roller 44 and longitudinally slot-
ted to accommodate the stitcher. The roller
115 44 is supported by the vertically adjustable
rod 45 while the foot 46 is supported by the
rod 47, both being carried by the bracket 48
and the adjustment being provided to adapt
them to varying thicknesses of work.

To further hold the work down to the way
120 and centered thereon I provide a V grooved
roller 272 which engages the work at the rear
of but close to the stitching point.

The work is carried through the stitcher,
125 while supported by the stitcher way 41 which
is, in fact, a work table for the stitcher, by
the coating feed rollers 49 and 50. The roll-
er 49 is disposed below the stitcher way and
in alignment with the slot 51 thereof while

the roller 50 is disposed above the stitcher way in opposed relation to the roller 49 so that the work is engaged by these rollers and positively carried through the stitcher. The 5 driving means for these rollers will be described later.

From the stitcher conveyor the work is delivered or passed to the discharge conveyor which consists of a plurality of idler supporting rollers 52 having journals 53 selectively engageable with notch-like bearings 54 in the spaced horizontally disposed bars 55. A plurality of driving rollers 56, 56' are provided to coact with certain of the idler rollers, the driving roller 56 being first in the series and having a special control means as will later be described.

These driving rollers are suitably spaced to carry the work along on the supporting 20 rollers and discharge the same to the delivery conveyor. These discharge conveyor driving rollers have friction rims or facings of rubber or suitable composition indicated at 57. The shafts 58 of these feed rollers 56 are supported in housings 59 and connected by beveled gears indicated conventionally at 60 by dotted lines, see Fig. 6, one of each pair of beveled gears having a sliding key connection to the shaft 61 so that the rollers 56 25 may be adjusted relative to each other and to the supporting rollers 52 by sliding the housing along on the shaft 61.

The housings 59 are supported at their forward ends on the supporting bar 62, adjustable housing holders 63 being mounted on the bar 62 and provided with set screws 64 by which they are retained in their adjusted positions. Adjustable supports 65 are threaded through ears 66 on the housings to engage 40 the bar 62, limiting the downward movement of the driving rollers. Winged lock nuts 67 are provided for these supports 65. The driving means for the shaft 61 will be described later.

45 As the work is carried along it comes into engagement with the rearwardly inclined arms 250 disposed on opposite sides of the bars 55. A pair of guide bars 251 are adjustably mounted on the upright 252 at the inner side of the delivery conveyor to assist in controlling and positioning the work as it is discharged on to the stacking or discharge conveyor.

55 At the front side of the path of the work and projecting over the discharge conveyor apron 68 is a second pair of arms 253 adjustably mounted on the upright 254. The stitched work is delivered from this discharge conveyor to a stacking or final delivery apron 68 which is disposed transversely at the rear end of the machine and supported by the rollers 69 and 70. The work is delivered from the belt or apron 68 to a table 71 upon which the work is delivered in a stack as shown by 60 dotted lines in Fig. 2. The work is removed

from this table 71 by an operator, or it might be otherwise delivered by the apron 68, as desired.

To align the work as it falls on the apron I provide an adjustable stop member 72 which 70 is carried by a clamp 73 adjustably secured to the end plate 74 by means of the set screw 255. The stop member 72 is tiltingly mounted on the clamp and has a pivot 256 engaging the clamp and secured in its adjusted position by the set screw 257.

The delivery conveyor frame 75 is carried by an upright 77 provided with a rack 78, the upright being supported for vertical adjustment in a bearing 79 on the end of an arm 80 or bracket 80 projecting rearwardly from the main frame of the machine, see Figs. 2, 11 and 12. The vertical adjustment is effected by means of shaft 81 having a pinion 82, see dotted lines in Fig. 12, meshing with the rack 78, 85 the shaft having a handwheel 83 at its outer end. The shaft also is provided with a ratchet wheel 84 and a coacting detent 85 is provided to hold the delivery conveyor in its adjusted position. This enables the rapid adjustment of the delivery conveyor to the requirements of the particular operator. The driving means for the delivery or stacking conveyor will be described later.

Having described the feed conveyor, the 95 stitching conveyor, the discharge conveyor and the final delivery conveyor and their relation to each other, I will now describe the driving mechanism by means of which these parts are operated in proper synchronism, and 100 by means of which the machine is adapted to different sizes of work and by means of which the spacing of the stitching is varied.

The machine illustrated is driven from the motor 86 which is mounted on a bracket 87 at 105 the rear of the machine. The main driving shaft 88 is connected to the motor through the gear 89 which is provided with a housing 89', see Figs. 3, 17 and 18. This gear is connected to the shaft 88 by means of a clutch controlled 110 from the foot pedal 90.

The driving clutch member 91 is of the cone type and carried by the gear while the driven clutch member 92 is fixed to the end of the shaft, see Fig. 18. A brake is combined with 115 this clutch and a relatively fixed conical brake member 93 is mounted on the frame to coact with the brake member 94 on the clutch so that when the clutch is released the brake is engaged, thereby checking the momentum of the 120 machine.

The shaft 88 is provided with a tubular extension 95 secured to the shaft by the key 96. The gear 89 is rotatably mounted on this shaft extension while the combined clutch and brake member is slidably secured thereto by means of the key 96' arranged transversely through the slot 97 and secured to the hub of the brake member.

A spring 98 arranged within this shaft ex- 130

tension urges the clutch to engaging position and acts to release the brake. The tension of this spring is adjusted by means of the screw 99 at the end of the shaft extension, see Fig. 18. 5 The shaft extension 95 has a second transverse slot 100 in which is pivoted the lever 101. The lever is pivoted at 102 to coact with the push rod 103 arranged within the shaft extension.

On the projecting end of the lever 101 is a 10 roller 104 adapted to coact with the tappet 105 on the releasing lever 106 which is pivoted at 107 on the frame to be shifted into position to engage with the roller 104 as the shaft 88 revolves. This clutch releasing lever 106 is 15 controlled by means of the rotatable star-wheel shaped member 108 to which is connected a ratchet wheel 109, see Figs. 17 and 18. This ratchet wheel is actuated by the pawl 110 carried by the foot lever 90. The upper end 20 of the pawl is supported by a pin 111 engaging a slot 112 in the pawl. The spring 113 returns the pawl and also, through its connection thereto, the foot lever.

The star-wheel 108 has spaced lift portions 25 114 adapted to coact with the lever 106 to hold it in inoperative position, this lever being shown in inoperative position in Fig. 17.

Between each lift the member 108 is conformed to allow the releasing lever 106 under 30 the tension of the spring 115 to swing into the path of the roller 104, thereby disengaging the driving clutch and applying the brake. A succeeding actuation of the foot pedal swings the releasing lever to inoperative position 35 and this allows the clutch to reengage under the action of the spring 98.

The driving gear 89 is connected to the motor through a variable speed transmission designated generally by the numeral 116. The 40 details of this variable speed transmission are not illustrated in this relation as the same variable speed transmission is employed in the driving connections for the driving shaft to the feed conveyor. This second transmission between the driving shaft and the motor is housed in the gear box 3.

Referring more particularly to Figs. 13, 14 and 15, the transmission illustrated comprises a shaft 118 having a plurality of gears as 45 119, 120, 121, 122 and 123 keyed thereto and a tubular shaft 124 having a plurality of gears 125, 126, 127, 128 and 129 coacting with the gears on the shaft 118 in the order named.

The sliding key 130 is adjustable to connect any one of the gears on the shaft 124, thus providing a wide range or variation in speed. The key 130 is carried by a rack 131 which is adjusted from the handwheel 132 on the spindle 133, the spindle having a pinion 134 meshing with the rack. The teeth of the rack are annular so as to permit rotation of the rack with the shaft.

The gears on the shaft 118 are the driving gears of the transmission, the gear 123 being 65 connected to the main driving shaft 88 by

the gear 135. This transmission is connected to the shaft 27, see Figs. 8 and 15, by a driving means which permits the adjustment of the feed conveyor chain so as to properly position the flights for the delivery of pamphlets 70 of different sizes to the stitching conveyor means.

The driving connection consists of a gear 140 on the shaft 124 which meshes with a gear 141 on the shaft 142, this shaft 142 having a 75 gear 143 on its upper end meshing with a gear 144 on the feed conveyor driving shaft 27. The shaft 142 is made up of sections connected by a coupling consisting of a pair of disks 145 and 146 on the ends of the section, 80 see Figs. 1, 13 and 18A. The disk 146 has a segmental slot 147 therein to receive the bolt 148. When this bolt is loosened the upper section, which is provided with graduations as indicated, may be turned relative to the 85 lower coupling member which is provided with a pointer, see Fig. 13, thereby moving the feed conveyor chain and through it adjusting the flights in proper relation to other parts of the mechanism. This adjustment 90 complements the bodily adjustment of the conveyor through its bearing slides 18 and 19 as has been described.

The work feed rollers 49 and 50 are driven from a shaft 152. This shaft 152 is connected to the shaft 153 for driving the lower feed roller 49 by means of the vertical shaft 154 having beveled gears 155 and 156 at its ends, the gear 155 meshing with the gear 157 on the shaft 152. The gear 156 meshes with 100 a gear 158 on the shaft 153.

The roller 49 is carried by a shaft 159 having a beveled gear 160 meshing with the beveled gear 161 on the shaft 153. The co-acting feed roller 50 is provided with a shaft 105 162 disposed in a swinging support or housing 164 pivoted on a shaft 167. The shaft 162 is provided with a beveled gear 165 meshing with the gear 166 on the shaft 167. The shaft 167 is connected to the shaft 152 by 110 means of the vertical shaft 168 and the beveled gears 171 and 172 on the shafts 168 and 167, respectively, and the beveled gears 169 and 170 on the shafts 168 and 152, respectively. 115

With this connection the upper and lower feed rollers 49 and 50 are driven at the same speed. The shaft 152 is driven with a variable stroke or motion illustrated in detail in Figs. 19 to 24, inclusive. The general relation of the parts is shown in Fig. 1.

This driving connection comprises a crank disk 173 which is pinned to the shaft 88 and carries an adjustable wrist pin 174 eccentrically mounted on a disk 175 rotatable in 125 an eccentrically disposed recess 176 in the crank disk. This pin carrying disk is secured in its adjusted position by set-screws 177, see Fig. 23. The crank pin disk 175 is provided with graduations or indicia operatively 130

associated with a pointer 179 on the crank disk.

The wrist pin 174 is connected to the oscillating rack 180 by means of the pitman 181. This rack is further controlled from a crank pin 182 on the shaft 183, this crank pin being connected to the lower end of the arm 184 on the rack by means of the pitman 185. The result is that the pivot 186 for the 10 rack is movably supported and the throw of the rack is varied by the movement of the pivot.

The crank shaft 183 is driven from the shaft 88, a gear 187 on the crank shaft meshing with a gear 188 on the shaft 88, see Figs. 15 23 and 24. The rack 180 is supported in mesh with the pinion 189 by means of the suspending link 190. The pinion 189 has a ratchet connection with the shaft 152, the 20 ratchet being indicated generally by the numeral 191.

The clincher bar 192 of the stapler is actuated in synchronism with the movement of the feed rollers through a double lobed cam 25 194 on the shaft 88 acting upon an arm 195 on the bell crank lever 196, one arm of which carries the supporting slide 197 of the clincher bar 192. The partially set staple is indicated at 198 in Fig. 19, bending members 30 199 deflecting the ends of the staple as shown in Fig. 19 to be engaged by the clinching bar 192 on its upward movement, thereby closing the staple or stitch, as it is commonly designated. The clincher bar is actuated 35 twice for each stitch thereby preventing clogging if the stitcher operates when there is no work to receive the stitches.

The cranks 173 and 182 are timed to rotate at different speeds so that as a result of the 40 variation in the pivot point of the rack or segment 180, a variation in the feeding movement of the work feed rollers results, thereby varying the spacing of the staples as indicated in Fig. 27.

The feed roller 50 is swung to and from feeding position or operative position relative to the feed roller 40 by the mechanism illustrated in Figs. 3, 5, 7 and 7A. As stated, the support 164 is tiltly or pivotally 45 mounted on the shaft 167 and is provided with an arm 200 which is engaged by a pin 204 on the arm 205 on the rockshaft 203. This rockshaft has an arm 206 thereon connected by a link 207 to the actuating lever 208.

This lever 208 is connected to the upper end of the link 209 which projects through the gear box 117, the lower end of the link being connected to the lever 210 actuated by a cam 50 consisting of a pair of cam members 211 and 212 adjustable relative to each other providing means for varying the cam. The cam 211 has a hub or sleeve 213 provided with adjusting indicia 214, an index 215 being operatively associated therewith. The clamping nut 216 55 holds the cam members in their adjusted posi-

tion on the shaft 124, see Figs. 13, 14 and 15. This adjustment provides for timing of the work feed roller, that is, the timing of engagement and disengagement.

The feed roller 50 is urged yieldingly into 70 feeding engagement by the spring pressed plunger 217, see Fig. 5, while the rockshaft 203 is provided with a spring pressed plunger 218. As stated, the stitcher head 4 employed may be of any suitable commercial type, that 75 is, the type manufactured as a unit. I do, however, provide improvements in the driving and adjusting means therefor.

The first driving roller 56 of the delivery conveyor is moved to and from operative relation to its coacting idler by means of a lever 260 which is pivoted at 261 and connected by the link 262 to the rearwardly projecting lugs 263 on the housing for the shaft of this roller, see Figs. 2, 7 and 7A. The lever 260 is actuated from an arm 264 on the rockshaft 203, the arm having a pin 265 engaging the end of the lever. With this arrangement the delivery roller 56 is thrown out of engagement with the work so that the delivery roller is 80 out of operative engagement with the work during the period it is acted upon by the feed roller, which prevents the work being pulled out of shape or distorted during the stitching operation. The delivery roller is thrown 85 into engagement with the work carrying it from the stitching position as soon as the work is released by the feed roller 50.

The stitcher driving shaft 219 is eccentrically mounted at 220 so that as the support is 90 rotated the stapler mechanism is adjusted to work of different thicknesses. On its outer end the support 220 is provided with a head 221 carrying a handle 222 which is threaded into the head so that it may be adjusted into 100 clamping relation to the fixed disk 223, see Figs. 3 and 5.

Power is transmitted to the shaft 219 through a shaft 224, the upper end of which is carried by a yoke 225 supported on the 110 shaft 219. The shaft 224 has a beveled gear 226 thereon meshing with a gear 227 on the shaft 219. On the lower end of the shaft 224 is a beveled gear 228 meshing with a gear 229 on the main driving shaft 88. The shaft 224 115 has a slip or sliding connection with the gear 228 as shown in Fig. 5.

The shaft 51 of the discharge conveyor is driven from the first transmission 116, the driving connections consisting of a gear 230 120 on a shaft 231 disposed on the side of the gear box and meshing with one of the driven gears of the transmission. This shaft 231 has a beveled gear 232 on its inner end meshing with the beveled gear 233 on the lower end 125 of the vertical shaft 234.

The shaft 234 is provided with a beveled gear 235 meshing with the beveled gear 236 on the shaft 237 disposed transversely of the machine, see Fig. 2. The shaft 237 is con- 130

nected to the shaft 61 by beveled gears indicated at 238, Fig. 2.

The delivery apron 68 is connected to the shaft 234 by means of the shaft 239 connected 5 to the shaft 234 by the gears 240 provided with a worm 241 meshing with a worm wheel 242 on the shaft 243. This shaft 243 is connected to the roller 69 by means of the beveled gears indicated at 244.

10 With the mechanism described the work in the form of signatures or leaves of a pamphlet to be stitched together is placed by the operator astride the feed conveyor 7 which has previously been adjusted according to the 15 length of the work. This adjustment should be such that the flights 10 are retracted at the point where the stitcher feed rollers engage the work to carry it through the stitcher. The control for the feed rollers is timed so 20 that the upper feed roller 50 is in retracted or inoperative position as the work is delivered into position to be engaged thereby so that the work freely passes below the same and is not distorted or fanned; that is, the 25 several sheets forming the work are not pulled out of position by the engagement of the feed rollers with the top and bottom sheets.

As the work is fed to the stitcher it passes 30 under the spring 43 which applies a slight friction so that there is no tendency for overthrow when the flights cease to carry the same forward.

The double conical roller 44 and the shoe 46 serve to hold the work in proper relation to 35 receive the stitches as it is fed into and through the stitcher.

By the driving means described the feed 40 rollers are driven with a variable stroke which results in variations in the spacing of the staples as is indicated in Fig. 27, the variation, of course, being uniform for each adjustment and capable of wide adaptation.

The machine is given further wide adaptability by the variation in speeds through the 45 mechanism described and the wide variation in the timing of the feeding action of the feed rollers. From the stitcher feed rollers the work is delivered to the discharge conveyor means described which is capable of ready 50 adjustment to the particular work.

The feed is varied according to the number of stitches desired in a given piece of work. For instance, where only two stitches are inserted in each piece of work the number of 55 pieces of work to be fed to the machine to maintain its capacity would be accordingly increased as compared with the number of pieces where six or eight stitches were made in each piece of work, and the transmissions 60 are adjusted and the feed control cam adjusted accordingly. This permits the adaptation of the machine for the particular work.

The work is fed to the machine by the work 65 delivery conveyor in position to receive the first stitch. This is of advantage in that it

enables the positioning of the first stitch relative to the end of the work so that the outer stitch does not interfere with trimming operations and the staples may be positioned in the work to permit cutting into a plurality of 70 perforations where that is required.

I have illustrated and described my improvements in an adaptation which has proven highly satisfactory. I have not attempted to illustrate or describe certain modifications or adaptations which I contemplate as it is believed the disclosure made will enable those skilled in the art to embody or adapt my improvements as may be desired.

Having thus described my invention, what 75 I claim as new and desire to secure by Letters Patent, is:

1. In a structure of the class described, the combination of a stitching mechanism, a work feed means for said stitching mechanism comprising a work way and a pair of coacting rollers, one of which is movable to and from work feeding position, means for intermittently driving said feed rollers with successive strokes of varying 80 length, a main variable speed driving transmission having a driving connection to said stitching mechanism and to said feed roller driving means, means for shifting said movable roller to and from work feeding position, 85 a second variable speed driving mechanism driven through said main variable speed driving mechanism and having driving connection to said roller shifting means, a work delivery conveyor delivering to said work feed means and comprising a work way and work translating means including a conveyor chain provided with flights whereby the work is delivered to initial stitching position, means for retracting said flights at work delivery 90 position, means for adjusting said work translating means to and from said work feed means, a driving connection for said work delivery translating means to said second variable speed transmission including 95 an adjusting means whereby the conveyor chain may be adjustable to vary the position of the flights relative to the actuating means therefor, a work discharge conveyor comprising a plurality of work supporting rollers adjustable relative to each other and a plurality of coacting driven rollers, the first of which is automatically movable to and from work engaging position, and operating connections 100 between said first roller and said movable feed roller shifting means whereby it is moved to inoperative position when said movable work feed roller is moved to operative position and vice versa.
2. In a structure of the class described, the combination of the stitching mechanism, a work feed means for said stitching mechanism comprising a work way and a pair of coacting rollers, one of which is movable to and from work feeding position, 105

means for intermittently driving said feed rollers with successive strokes of varying length, a main variable speed driving transmission having a driving connection to said 5 stitching mechanism and to said feed roller driving means, means for shifting said movable roller to and from work feeding position, a second variable speed driving mechanism driven through said main variable speed 10 driving mechanism and having driving connection to said roller shifting means, a work delivery conveyor delivering to said work feed means and comprising a work way and work translating means including a conveyor 15 chain provided with flights whereby the work is delivered to initial stitching position, means for retracting said flights at work delivery position, means for adjusting said work translating means to and from said 20 work feed means, and a driving connection for said work delivery means to said second variable speed transmission including an adjusting means whereby the conveyor chain may be adjusted to vary the position of the 25 flights relative to the actuating means therefor.

3. In a structure of the class described, the combination of a stitching mechanism, a work feed means for said stitching mechanism comprising a work way and a pair of coacting rollers, one of which is movable to and from work feeding position, means for intermittently driving said feed rollers with successive strokes of varying length, a main 35 variable speed driving transmission having a driving connection to said stitching mechanism and to said feed roller driving means, means for shifting said movable roller to and from work feeding position, a second variable 40 speed driving mechanism driven through said main variable speed driving mechanism and having driving connection to said roller shifting means, a work discharge conveyor comprising a plurality of work supporting 45 rollers adjustable relative to each other and a plurality of coacting driven rollers, the first of which is automatically movable to and from work engaging position, and operating connections between said first roller 50 and said movable feed roller shifting means whereby it is moved to inoperative position when said movable work feed roller is moved to operative position and vice versa.

4. In a structure of the class described, the combination of a stitching mechanism, a work feed means for said stitching mechanism comprising a work way and a pair of coacting rollers, one of which is movable to and from work feeding position, means for 55 intermittently driving said feed rollers with successive strokes of varying length, a main variable speed driving transmission having a driving connection to said stitching mechanism and to said feed roller driving means, means for shifting said movable roller to and 60

from work feeding position, and a second variable speed driving mechanism driven through said main variable speed driving mechanism and having driving connection to said roller shifting means. 70

5. In a structure of the class described, the combination of a stitching mechanism, a work feed means for said stitching mechanism comprising a work way and a pair of coacting rollers, one of which is movable to and from work feeding position, means for intermittently driving said feed rollers with successive strokes of varying length, said means being adjustable to vary the length of such strokes, a main variable speed driving 80 transmission having a driving connection to said stitching mechanism and to said feed roller driving means, means for shifting said movable roller to and from work feeding position including a timing cam comprising a pair of relatively adjustable cam members, and a second variable speed driving mechanism driven through said main variable speed driving mechanism and having driving connection to said timing cam. 85 90

6. In a structure of the class described, the combination of a stitching mechanism, a work feed roller operatively associated with said stitching mechanism and movable to and from work feeding position, means for intermittently driving said feed roller with successive strokes of varying length, a main variable speed driving transmission having a driving connection to said stitching mechanism and to said feed roller driving means, 95 means for shifting said roller to and from work feeding position including a timing cam, a second variable speed driving mechanism driven through said main variable speed driving mechanism and having driving connection to said timing cam, a work delivery means delivering to said work feed means and comprising a conveyor chain provided with flights, means for retracting said flights at work delivery position, means for adjusting said work delivery means to and from said work feed means, a driving connection for said work delivery means to said second variable speed transmission including an adjusting means whereby the conveyor chain may 100 be adjusted to vary the position of the flights relative to the actuating means therefor, a work discharge roller movable to and from work engaging position, and operating connections between said discharge roller and said feed roller shifting means whereby it is moved to inoperative position when said work feed roller is moved to operative position and vice versa. 105 110

7. In a structure of the class described, the combination of a stitching mechanism, a work feed roller operatively associated with said stitching mechanism and movable to and from work feeding position, means for intermittently driving said feed roller 120 125

130

with successive strokes of varying length, a main variable speed driving transmission having a driving connection to said stitching mechanism and to said feed roller driving means, means for shifting said roller to and from work feeding position including a timing cam, a second variable speed driving mechanism driven through said main variable speed driving mechanism and having 5 driving connection to said timing cam, a work discharge roller movable to and from work engaging position, and operating connections from said discharge roller to said feed roller shifting means whereby it is 10 moved to inoperative position when said work feed roller is moved to operative position and vice versa.

8. In a structure of the class described, the combination of a stitching mechanism, 20 a work feed roller operatively associated with said stitching mechanism and movable to and from work feeding position, means for intermittently driving said feed roller with successive strokes of varying length, a 25 main variable speed driving transmission having a driving connection to said stitching mechanism and to said feed roller driving means, means for shifting said roller to and from work feeding position including a 30 timing cam, and a second variable speed driving mechanism driven through said main variable speed driving mechanism and having driving connection to said timing cam.

35 9. In a structure of the class described, the combination of a stitching mechanism, a work feed roller operatively associated with said stitching mechanism and movable to and from work feeding position, means 40 for intermittently driving said feed roller with successive strokes of varying length, said means being adjustable to vary the length of such strokes, a main variable speed driving transmission having a driving connection to said stitching mechanism and to 45 said feed roller driving means, means for shifting said roller to and from work feeding position including a timing cam comprising a pair of relatively adjustable cam members, and a second variable speed driving mechanism driven through said main 50 variable speed driving mechanism and having driving connection to said timing cam.

55 10. In a structure of the class described, the combination of a stitching mechanism, a work feed means for said stitching mechanism comprising a roller movable to and from work feeding position, means for intermittently driving said feed roller with 60 successive strokes of varying length, said means being adjustable to vary the length of such strokes, and means for shifting said feed roller to and from work feeding position including a timing cam comprising a pair of relatively adjustable cam members.

11. In a structure of the class described, the combination of a stitching mechanism, a work feed means for said stitching mechanism comprising a roller movable to and from work feeding position, means for intermittently driving said feed roller with successive strokes of varying length, and means for shifting said feed roller to and from feeding position including a timing cam comprising a pair of relatively adjustable cam members. 70 75

12. In a structure of the class described, the combination of a stitching mechanism, a work feed means for said stitching mechanism comprising a roller movable to and from work feeding position, means for intermittently driving said feed roller with successive strokes of varying length, said means being adjustable to vary the length of such strokes, and means for shifting said feed roller to and from work feeding position including a timing means. 80

13. In a structure of the class described, the combination of a stitching mechanism, a work feed means for said stitching mechanism comprising a roller movable to and from work feeding position, means for intermittently driving said feed roller with successive strokes of varying length, and means for shifting said feed roller to and from work feeding position including a timing means. 90

14. In a structure of the class described, the combination of a stitching mechanism, a work feed means for said stitching mechanism comprising a roller movable to and from work feeding position, means for intermittently driving said feed roller, means for shifting said feed roller to and from work feeding position, a work delivery conveyor 100 means comprising a work way and translating means including a conveyor chain provided with flights, means for retracting said flights at work delivery position, means for adjusting said work translating means as a 105 unit to and from said work feed means, driving means for said work delivery translating means including an adjusting means whereby the conveyor chain may be adjusted to vary the position of the flights relative to the actuating means therefor, a work discharge roller movable to and from work engaging position, and operating connections from said discharge roller to said feed roller shifting means whereby the feed roller and the discharge roller are alternately moved to operative position. 110 115

15. In a structure of the class described, the combination of a stitching mechanism, a work feed means for said stitching mechanism comprising a roller movable to and from work feeding position, means for intermittently driving said feed roller, means for shifting said feed roller to and from work feeding position, a work delivery conveyor 120 125 means comprising a work way and translating means including a conveyor chain provided with flights, means for retracting said flights at work delivery position, means for adjusting said work translating means as a unit to and from said work feed means, driving means for said work delivery translating means including an adjusting means whereby the conveyor chain may be adjusted to vary the position of the flights relative to the actuating means therefor, a work discharge roller movable to and from work engaging position, and operating connections from said discharge roller to said feed roller shifting means whereby the feed roller and the discharge roller are alternately moved to operative position. 130

means comprising a work way and translating means including a conveyor chain provided with flights, means for retracting said flights at work delivery position, means for 5 adjusting said work translating means as a unit to and from said work feed means, and driving means for said work delivery translating means including an adjusting means whereby the conveyor chain may be adjusted 10 to vary the position of the flights relative to the actuating means therefor.

16. In a structure of the class described, the combination of a stitching mechanism, a work feed means for said stitching mechanism, a work delivery conveyor means comprising a work way and translating means including a conveyor chain provided with flights, means for retracting said flights at work delivery position, means for adjusting 15 20 said work translating means as a unit to and from said work feed means, and driving means for said work delivery translating means including an adjusting means whereby the conveyor chain may be adjusted to vary 25 the position of the flights relative to the actuating means therefor.

17. In a structure of the class described, the combination of a stitching mechanism, a work feed means including a member movable to and from work feeding position, means for driving said work feed member with successive feed strokes of varying length, means for shifting said feed member to and from feeding position including a 30 timing member, a variable speed driving means operatively connected with said stitching mechanism and said feed member driving means, a second variable speed driving means operatively associated with said 35 shifting means, a work delivery mechanism including a work translating means adjustable to and from said work feed means for adaptation to work of different longitudinal dimensions, a driving connection for said 40 work delivery translating means including an adjustable means supplementing the before-mentioned adjusting means for said work delivery translating means, a work 45 discharge means movable to and from operative position, and operating connections therefor from said work feed shifting means whereby said work discharge means is moved to inoperative position when the work feed 50 means is moved to operative position and vice versa.

18. In a structure of the class described, the combination of a stitching mechanism, a work feed means including a member movable to and from work feeding position, means for driving said work feed member with successive feed strokes of varying length, means for shifting said feed member to and from feeding position including a 55 timing member, a variable speed driving means operatively connected with said stitch-

ing mechanism and said feed member driving means, a second variable speed driving means operatively associated with said shifting means, a work delivery mechanism including a work translating means adjustable to and 70 from said work feed means for adaptation to work of different longitudinal dimensions, and a driving connection for said work delivery translating means including an adjustable means supplementing the before- 75 mentioned adjusting means from said work delivery translating means.

19. In a structure of the class described, the combination of a stitching mechanism, a work feed means including a member movable to and from work feeding position, means for driving said work feed member with successive feed strokes of varying length, means for shifting said feed member to and from feeding position including a timing member, a variable speed driving means operatively connected with said stitching mechanism and said feed member driving means, a second variable speed driving means operatively associated with said shifting 80 85 means, a work discharge means movable to and from operative position, and operating connections therefor from said shifting means whereby said work discharge means is moved to inoperative position when the work feed 90 means is moved to operative position and vice versa.

20. In a structure of the class described, the combination of a stitching mechanism, a work feed means including a member movable to and from work feeding position, means for driving said work feed member with successive feed strokes of varying length, means for shifting said feed member to and from feeding position including a timing member, a variable speed driving means operatively connected with said stitching mechanism and said feed member driving means, and a second variable speed driving means operatively associated with said shifting 100 105 means. 110

21. In a structure of the class described, the combination of a stitching mechanism, a work feed means comprising a pair of oppositely inclined way members, one of said way members having an opening therethrough, a pair of coacting feed rollers aligned with said opening, means for intermittently driving said feed rollers with successive strokes of varying length, said means being adjustable to vary the length of such strokes, a feed roller control means acting to move one of said feed rollers to and from work driving position, and means for varying the timing of said feed roller control means. 115 120

22. In a structure of the class described, the combination of a stitching mechanism, work feed means operatively associated therewith and comprising a work supporting way, co-acting feed rollers, one of which is movably mounted to be shifted to and from feeding 125 130

position, means for intermittently driving said rollers with strokes of varying length, means for shifting said movable roller to and from feeding position including an adjustable timing means, a main variable speed driving means having variable connection to said stitching mechanism and to said feed roller driving means, and a second variable speed driving mechanism driven from said 10 first mentioned variable speed driving mechanism and having driving connection to said timing means.

23. In a structure of the class described, the combination of a stitching mechanism, work feed means operatively associated therewith and comprising a work supporting way, co-acting feed rollers, one of which is movably mounted to be shifted to and from feeding position, means for intermittently driving 15 said rollers, means for shifting said movable roller to and from feeding position, a main variable speed driving means having variable connection to said stitching mechanism and to said feed roller driving means, and a second variable speed driving mechanism driven from said 20 first mentioned variable speed driving mechanism and having driving connection to said shifting means.

24. In a structure of the class described, the combination of a stitching mechanism, a work feed means comprising a feed roller, means for intermittently driving said feed roller with successive strokes of varying length, said means being adjustable to vary the 25 length of such strokes, a main variable speed driving means having driving connections to said stitching mechanism and to said feed roller driving means, a feed roller control means acting to move said feed roller to and 30 from work driving position, a variable speed transmission for said feed roller control means having driving connection to said main variable speed driving transmission, and means for varying the timing of said feed 35 roller control means.

25. In a structure of the class described, the combination of a stitching mechanism, a work feed means comprising a feed roller, means for intermittently driving said feed 40 roller with successive strokes of varying length, a main variable speed driving means having driving connections to said stitching mechanism and to said feed roller driving means, a feed roller control means acting to 45 move said feed roller to and from work driving position, and a variable speed transmission for said feed roller control means having driving connection to said main variable speed driving transmission.

26. In a structure of the class described, the combination of a stitching mechanism, a work feed means including a member movable to and from work feeding position, means for driving said work feed member with successive feed strokes of varying length, said 55

means being adjustable to vary the length of such feed strokes, means for shifting said feed member to and from feeding position including an adjustable timing member, a work delivery mechanism including a work translating means adjustable to and from said work feed means for adaptation to work of different longitudinal dimensions, a work discharge means movable to and from operative position, and operating connections therefor 60 to said shifting means whereby said work discharge means is moved to inoperative position when the work feed means is moved to operative position and vice versa.

27. In a structure of the class described, the combination of a stitching mechanism, a work feed means including a member movable to and from work feeding position, means for driving said work feed member with successive feed strokes of varying length, 65 said means being adjustable to vary the length of such feed strokes, means for shifting said feed member to and from driving position including an adjustable timing member, and a work delivery mechanism including a work translating means adjustable to and from said work feed means for adaptation to work of different longitudinal dimensions.

28. In a structure of the class described, the combination of a stitching mechanism, a work feed means including a member movable to and from work feeding position, means for driving said work feed member with successive feed strokes of varying length, said 70 means being adjustable to vary the length of such feed strokes, means for shifting said feed member to and from feeding position including an adjustable timing member, a work discharge means movable to and from operative position, and operating connections therefor to said shifting means whereby said work discharge means is moved to inoperative position when the work feed means is moved to operative position and vice versa.

29. In a structure of the class described, the combination of a stitching mechanism, a work feed means including a member movable to and from work feeding position, means for driving said work feed member with successive feed strokes of varying length, said means being adjustable to vary the length of such feed strokes, and means for shifting said feed member to and from feeding position including an adjustable timing member.

30. In a structure of the class described, the combination of a stitching mechanism, a work feed roller operatively associated with said stitching mechanism and movable to and from work feeding position, means for shifting said roller to and from work feeding position including a timing cam comprising a pair of relatively adjustable cam members, a work discharge roller movable to and from work engaging position, and operating con- 125

nections from said discharge roller to said feed roller shifting means whereby the discharge roller and the feed roller are alternated to operative position.

5 31. In a structure of the class described, the combination of a stitching mechanism, a work feed roller operatively associated with said stitching mechanism and movable to and from work feeding position, and means for 10 shifting said roller to and from work feeding position including a timing cam comprising a pair of relatively adjustable cam members.

32. In a structure of the class described, the combination of a stitching mechanism, a work 15 feed means comprising a feed roller, means for driving said feed roller with successive strokes of varying length, said means being adjustable to vary the length of such strokes, a feed control means acting to move said 20 feed roller to and from work engaging position, and means for varying the timing of said feed control means.

33. In a structure of the class described, the combination of a stitching mechanism, a work 25 feed means comprising a feed roller, and means for driving said feed roller with successive strokes of varying length, said means being adjustable to vary the length of such 30 strokes.

34. In a structure of the class described, the combination of a stitching mechanism, a work feed means comprising a feed roller, means for driving said feed roller with successive strokes of varying length, a feed 35 control means acting to move said feed roller to and from work engaging position, and means for varying the timing of said feed control means.

35. In a structure of the class described, the 40 combination of a stitching mechanism, a work feed means comprising a feed roller, means for shifting said feed roller to and from feeding position, and means for driving said feed roller with successive strokes of 45 varying length.

36. In a structure of the class described, the combination of a stitching mechanism, a work feed means operatively associated therewith and comprising a feed roller adjustably mounted to be moved to and from feeding position, a variable speed driving means for said feed roller, and means for varying the effective period of actuation of said feed roller for varying the spacing of 50 the stitches.

37. In a structure of the class described, the combination of a stitching mechanism, an intermittently acting work feed means, whereby the work is fed to varying positions relative to the stitching mechanism, a feed delivery means adjustable to position the work delivered to the said work feed means and to work of different sizes, driving connections for said work feed means and work delivery 55 means permitting such adjustment, and

means for varying the length of the feed stroke of said work feed means independently of said delivery means and of the position to which the work is delivered by said delivery means.

38. In a structure of the class described, the combination of a stitching mechanism, a work feed means for said stitching mechanism comprising a feeding roller movable to and from work driving position, means for 70 intermittently driving said feed roller, means for shifting said roller to and from work feeding position including a timing means adjustable to vary the timing of actuation of said feed roller, a work discharge means comprising a plurality of work supporting rollers adjustable relative to each other and a plurality of coacting driven rollers, the first of which is automatically movable to and from work driving position to engage the work released by said feed roller, and operating connections for said automatically movable discharge roller to said movable work feed roller shifting means whereby said work feed and discharge rollers are alternately moved to 75 and from operative position. 80

39. In a structure of the class described, the combination of a stitching mechanism, a work feed means for said stitching mechanism comprising a feed roller movable to and from work driving position, means for intermittently driving said feed roller, means for shifting said roller to and from work driving position, a work discharge means comprising a plurality of work supporting 90 rollers adjustable relative to each other and a plurality of coacting driven rollers, the first of which is automatically movable to and from work engaging position to engage the work released by said feed roller, and operating connections for said automatically movable discharge roller to said movable work feed roller shifting means whereby said work feed and discharge rollers are alternately moved to 95 and from operative position. 100

40. In a structure of the class described, the combination of a stitching mechanism, a work feed means for said stitching mechanism comprising a feed roller movable to and from work feeding position, means for intermittently driving said feed roller, means for shifting said roller to and from work driving position including a timing means adjustable to vary the timing or actuation of said feed roller, a work discharge means comprising a driven roller movable to and from work engaging position to engage the work released by said feed roller, and operating connections from said discharge roller to 115 said work feed roller shifting means whereby said work feed and discharge rollers are alternately moved to and from operative position. 120

41. In a structure of the class described, the combination of a stitching mechanism, a 125 work feed means comprising a feed roller movable to and from work driving position to engage the work released by said feed roller, and operating connections from said discharge roller to said work feed roller shifting means whereby said work feed and discharge rollers are alternately moved to and from operative position.

42. In a structure of the class described, the combination of a stitching mechanism, a 130

- work feed means therefor, a work delivery conveyor operatively associated therewith and comprising a work way and translating means including a conveyor chain provided 5 with flights whereby the work is delivered to initial stitching position, means for retracting said flights at work delivery position, means for adjusting said work translating means to and from said work feed means 10 as a unit, and a driving connection for said work feed translating means including an adjusting means whereby the conveyor chain may be adjusted to vary the position of its flights relative to said feed means.

15 42. In a structure of the class described, the combination of a stitching mechanism, a work delivery conveyor operatively associated therewith and comprising a work way and translating means including a conveyor 20 chain provided with flights whereby the work is delivered to initial stitching position, means for retracting said flights at work delivery position, and means for adjusting said work translating means to and 25 from said work feed means as a unit.

43. In a structure of the class described, the combination of a stitching mechanism, an intermittently acting work feed means, driving means for said feed means, means 30 for varying the length of the feed between predetermined stitches, a feed conveyor operatively associated with said feed means and comprising conveyor flights, means for adjusting said conveyor mechanism as a unit, 35 a variable speed driving means, and driving connections for said conveyor to said variable speed driving means including an adjusting mechanism whereby the conveyor flights may be adjusted relative to said feed means.

40 44. In a structure of the class described, the combination of a stitching mechanism, an intermittently acting work feed means, means for varying the length of the feed between predetermined stitches, a feed conveyor operatively associated with said 45 stitcher feed means, and means for adjusting said conveyor mechanism as a unit.

45. In a structure of the class described, the combination of a stitching mechanism, a work delivery conveyor comprising way members disposed in oppositely inclined relation with their upper edges spaced, supporting rails disposed below said work way members, bearing blocks connected in spaced 50 relation and slidably adjustable on said supporting rails, one of said rails being provided with scale indicia and one of said bearing blocks with a pointer operatively associated therewith, means for securing said bearing blocks in their adjusted positions on said rails, a conveyor chain, supporting and driving sprockets therefor carried by said bearing blocks, flights pivotally mounted on said conveyor chain and having laterally disposed 55 supporting arms provided with rollers, said flights having tappets on their pivots, a channeled flight supporting way coacting with said rollers to support said flights in erect position while traveling along the upper reach of the conveyor, and flight retracting 60 members disposed at the forward ends of said supporting way to be engaged by said tappets when the rollers pass from their said supporting way whereby the flights are retracted at work delivery position, said flight supporting way having a flight erecting 65 guide at its forward end.

46. In a structure of the class described, the combination of a stitching mechanism, a work delivery conveyor comprising way members disposed in oppositely inclined relation with their upper edges spaced, supporting rails disposed below said work way members, bearing blocks connected in spaced 70 relation and slidably adjustable on said supporting rails, a conveyor chain, supporting and driving sprockets therefor carried by said bearing blocks, flights pivotally mounted on said conveyor chain and having laterally disposed supporting arms provided with rollers, said flights having tappets on their pivots, a channeled flight supporting way coacting with said rollers to support said flights in erect position while traveling along the upper reach of the conveyor, and flight retracting 75 members disposed at the forward ends of said supporting way to be engaged by said tappets when the rollers pass from their said supporting way whereby the flights are retracted at work delivery position, said flight supporting way having a flight erecting 80 guide at its forward end.

47. In a structure of the class described, the combination of a stitching mechanism, a work delivery conveyor comprising way members disposed in oppositely inclined relation with their upper edges spaced, supporting rails disposed below said work way members, bearing blocks connected in spaced 85 relation and slidably adjustable on said supporting rails, a conveyor chain, supporting and driving sprockets therefor carried by said bearing blocks, flights pivotally mounted on said conveyor chain and having laterally disposed supporting arms provided with rollers, said flights having tappets on their pivots, a channeled flight supporting way coacting with said rollers to support said flights in erect position while traveling along the upper reach of the conveyor, and flight retracting 90 members disposed at the forward ends of said supporting way to be engaged by said tappets when the rollers pass from their said supporting way whereby the flights are retracted at work delivery position, said flight supporting way having a flight erecting 95 guide at its forward end.

48. In a structure of the class described, the combination of a stitching mechanism, a work delivery conveyor comprising way members disposed in oppositely inclined relation with their upper edges spaced, supporting rails disposed below said work way members, bearing blocks connected in spaced 100 relation and slidably adjustable on said supporting rails, a conveyor chain, supporting and driving sprockets therefor carried by said bearing blocks, flights pivotally mounted on said conveyor chain and having laterally disposed supporting arms provided with rollers, said flights having tappets on their pivots, a channeled flight supporting way coacting with said rollers to support said flights in erect position while traveling along the upper reach of the conveyor, and flight retracting 105 members disposed at the forward ends of said supporting way to be engaged by said tappets when the rollers pass from their said supporting way whereby the flights are retracted at work delivery position, said flight supporting way having a flight erecting 110 guide at its forward end.

49. In a structure of the class described, the combination of a stitching mechanism, a work delivery conveyor comprising way members disposed in oppositely inclined relation with their upper edges spaced, supporting rails disposed below said work way members, bearing blocks connected in spaced 115 relation and slidably adjustable on said supporting rails, a conveyor chain, supporting and driving sprockets therefor carried by said bearing blocks, one of said sprockets being provided with a beveled gear, a driven shaft with which one of said bearing blocks is slidably associated, gear splined on said shaft to coact with said gear on said sprocket, flights pivotally mounted on said conveyor chain and having laterally disposed supporting arms provided with rollers, said flights having tappets on their pivots, a channeled flight supporting way coacting with said rollers to support said flights in erect position while traveling along the upper reach of the conveyor, and flight retracting 120 members disposed at the forward ends of said supporting way to be engaged by said tappets when the rollers pass from their said supporting way whereby the flights are retracted at work delivery position, said flight supporting way having a flight erecting 125 guide at its forward end.

- flights are retracted at work delivery position, said flight supporting way having a flight erecting guide at its forward end.
48. In a structure of the class described, the 5 combination of a stitching mechanism, a work delivery conveyor comprising way members disposed in oppositely inclined relation with their upper edges spaced, supporting rails disposed below said work way members, bearing 10 blocks slidably adjustable on said supporting rails, one of said rails being provided with scale indicia and one of said bearing blocks with a pointer operatively associated therewith, means for securing said bearing blocks 15 in their adjusted positions on said rails, a conveyor chain, supporting and driving sprockets therefor carried by said bearing blocks, flights pivotally mounted on said conveyor chain, a flight supporting way coacting 20 with said flights to support them in erect position while traveling along the upper reach of said conveyor, and flight retracting means at the forward ends of said supporting way whereby the flights are retracted at work delivery 25 position.
49. In a structure of the class described, the combination of a stitching mechanism, a work delivery conveyor comprising way members disposed in oppositely inclined relation with 30 their upper edges spaced, supporting rails disposed below said work way members, bearing blocks slidably adjustable on said supporting rails, one of said rails being provided with scale indicia, a conveyor chain, supporting and driving sprockets therefor carried by said bearing blocks, flights pivotally mounted on said conveyor chain, a flight supporting way coacting with said flights to support them in erect position while traveling 35 along the upper reach of said conveyor, and flight retracting means at the forward ends of said supporting way whereby the flights are retracted at work delivery position.
50. In a structure of the class described, the 45 combination of a stitching mechanism, a work delivery conveyor comprising way members disposed in oppositely inclined relation with their upper edges spaced, supporting rails disposed below said work way members, bearing blocks slidably adjustable on said supporting rails, one of said rails being provided with scale indicia, a conveyor chain, supporting and driving sprockets therefor carried by said bearing blocks, one of said 50 sprockets being provided with a beveled gear, a driven shaft with which one of said bearing blocks is slidably associated, a gear splined on said shaft to coact with said gear on said sprocket, flights pivotally mounted on said conveyor chain, a flight supporting way coacting with said flights to support them in erect position while traveling along the upper reach of said conveyor, flight retracting means at the forward ends of said supporting 55 way whereby the flights are retracted at work
- delivery position, and driving means for said shaft including an adjustable connection whereby the flights may be positioned relative to the driving means.
51. In a structure of the class described, the 70 combination of a stitching mechanism, a stitching mechanism work feed, a work delivery conveyor provided with work engaging flights adapted to deliver the work to initial stitching position, means for retracting the flights at work stitching position, means for adjusting said conveyor to and from the stitching mechanism as a unit, and independent means for adjusting the flights 75 relative to the conveyor.
52. In a structure of the class described, the combination of a stitching mechanism, a stitching mechanism work feed, a work delivery conveyor provided with work engaging flights adapted to deliver the work to initial 80 stitching position, means for retracting the flights at work stitching position, and means for adjusting said conveyor to and from the stitching mechanism as a unit.
53. In a structure of the class described, the combination of a stitching mechanism, a work feed means therefor comprising a feed roller shiftable to and from work driving position, means for shifting the feed roller, a discharge conveyor comprising a pair of 85 spaced bars having notch-like bearings in their upper edges, a plurality of work supporting idlers provided with journals selectively engageable with said bearings of said bars, a driving shaft, a plurality of driven 90 rollers, shafts for said driven rollers provided with housings pivotally and slidably mounted on said driving shaft, a supporting bar for said housings, adjustable stops on said housings coacting with said bar for positioning said driven rollers relative to said idlers, driving connections for said driven 95 roller shafts to said driving shaft permitting the adjustment of said housings, and operating connections from the first of said driven 100 rollers to said feed roller shifting means whereby the driven roller and the feed roller are alternately moved to and from work engaging position.
54. In a structure of the class described, the combination of a stitching mechanism, a work feed means therefor, a discharge conveyor comprising a pair of spaced bars having notch-like bearings in their upper edges, a plurality of work supporting idlers provided with journals selectively engageable with said bearings of said bars, a driving 110 shaft, a plurality of driven rollers, shafts for said driven rollers provided with housings pivotally and slidably mounted on said driving shaft, a supporting bar for said housings, adjustable stops on said housings coacting with said bar for positioning said driven rollers relative to said idlers, and driving connections for said driven roller 115

- 125
- 130

shafts to said driving shaft permitting the adjustment of said housings.

55. In a structure of the class described, the combination of a stitching mechanism, a work feed means therefor comprising a feed roller shiftable to and from work driving position, means for shifting the feed roller, a discharge conveyor comprising a plurality of work supporting rollers, a driving shaft, 5 a plurality of driven rollers, shafts for said driven rollers provided with housings pivotally and slidably mounted on said driving shaft, a supporting bar for said housings, adjustable stops on said housings coacting 10 with said bar for positioning said driven rollers relative to said supporting rollers, driving connections for said driven roller shafts to said driving shaft permitting the adjustment of said housings, and operating connections 15 from the first of said driven rollers to said feed roller shifting means whereby the feed roller and the driven roller are alternately moved to and from work engaging 20 position.
- 25 56. In a structure of the class described, the combination of a stitching mechanism, a work feed means therefor, a discharge conveyor comprising a plurality of work supporting rollers, a driving shaft, a plurality 30 of driven rollers, shafts for said driven rollers provided with housings pivotally and slidably mounted on said driving shaft, a supporting bar for said housings, adjustable stops on said housings coacting with said bar 35 for positioning said driven rollers relative to said supporting rollers, and driving connections for said driven roller shafts to said driving shaft permitting the adjustment of said housings.
- 40 57. In a structure of the class described, the combination of a stitching mechanism, a work feed means therefor comprising a feed roller shiftable to and from work feeding position, means for shifting the feed roller, a 45 discharge conveyor comprising a plurality of work supporting rollers mounted for adjustment longitudinally of the conveyor, a plurality of driven rollers mounted for adjustment longitudinally of the conveyor to 50 cooperate with said supporting rollers, said rollers being independently adjustable, and operating connections from one of said driven rollers to said feed roller shifting means whereby the feed roller and the driven 55 roller are alternately moved to and from work engaging position.

58. In a structure of the class described, the combination of a stitching mechanism, a work feed means therefor, a discharge conveyor comprising a plurality of work supporting rollers mounted for adjustment longitudinally of the conveyor, and a plurality 60 of driven rollers mounted for adjustment longitudinally of the conveyor to cooperate

with said supporting rollers, said rollers being independently adjustable. 65

59. In a structure of the class described, the combination of a stitching mechanism, a work feed means therefor, a discharge conveyor comprising a plurality of work supporting rollers mounted for adjustment longitudinally of the conveyor, a plurality of driven rollers mounted for adjustment longitudinally of the conveyor to cooperate with said supporting rollers, said rollers being independently adjustable, and adjustable means for vertically supporting said driven rollers. 70 75

60. In a stitching machine, the combination with a single stitcher head, of a work feed means operatively associated therewith and comprising a roller shiftable to and from work feeding position, means for intermittently driving said roller with successive strokes of varying length, said means being adjustable to vary the length of such strokes, 80 a variable speed driving means operatively connected with said stitching mechanism and feed roller driving means, and means operatively associated with said roller for shifting it to and from work feeding position including a variable speed driving means. 85

61. In a stitching machine, the combination with a single stitcher head, of a work feed means operatively associated therewith and comprising a roller shiftable to and from work feeding position, means for intermittently driving said roller, a variable speed driving means operatively connected with said stitching mechanism and feed roller driving means, and means operatively associated with said roller for shifting it to and from work feeding position including a variable speed driving means. 90 95

62. In a stitching machine, the combination with a single stitcher head, of work feed means operatively associated therewith and comprising a member shiftable to and from work feeding position, means for driving said feed member with successive strokes of varying length, said means being adjustable to vary the length of such stroke, a variable speed driving means operatively connected with said stitching mechanism and work feed means, and means for shifting said work feed member to and from work feeding position including an adjustable timing means. 105 110 115

63. In a stitching machine, the combination with a single stitcher head, of work feed means operatively associated therewith and comprising a member shiftable to and from work feeding position, means for driving said feed member, a variable speed driving means operatively connected with said stitching mechanism and work feed means, and means for shifting said work feed member to and from work feeding position including an adjustable timing means. 120 125

64. In a stitching machine, the combination

with a stitching mechanism head, of work feed means adjustable to vary the length of feed strokes, a variable speed driving means operatively associated with said stitching mechanism and feed means, and a variable speed timing means for said feed means.

65. In a stitching machine, the combination with a stitching mechanism head, of work feed means, a variable speed driving means operatively associated with said stitching mechanism and feed means, and a variable speed timing means for said feed means.

66. In a stitching machine, the combination of a single stitcher head, a work feed means operatively associated therewith comprising a feed roller shiftable to and from work feed-

ing position, means for driving said roller with successive strokes of varying length, and means for shifting said driving roller including a variable speed driving mechanism. 20

67. In a stitching machine, the combination with a single stitcher head, of variable stroke work feed means adjustable to vary the length of feed strokes, a variable speed driving means operatively associated with said stitching mechanism and feed means, and a variable speed timing means for said feed means, said variable speed means being independently adjustable.

In witness whereof I have hereunto set my hand.

FRED L. MANNY.
